UNITED STATES PATENT OFFICE.

ELTON R. SHAW, OF SAN FRANCISCO, ASSIGNOR TO MOSHER, SHAW & CRAIG, OF SAN JOSE, CALIFORNIA.

DRIER.

SPECIFICATION forming part of Letters Patent No. 427,198, dated May 6, 1890.

Application filed April 6, 1889. Serial No. 306,249. (No model.)

To all whom it may concern:

Be it known that I, ELTON R. SHAW, of the city and county of San Francisco, State of California, have invented an Improvement in 5 Driers; and I hereby declare the following to be a full, clear, and exact description of the same.

My invention relates to the class of driers or evaporators for fruit, vegetables, &c.; and 10 my invention consists in the constructions and combinations of devices which I shall hereinafter fully describe and claim.

A difficulty in driers is a failure to dry uniformly in all parts of the drier—a necessary 15 operation to enable the material under treatment to emerge in as near a uniform degree of desiccation as will insure its proper keeping qualities, color, and flavor. My drier is intended to overcome this difficulty, as well as 20 to enable the operators to handle their work with facility and profit.

Referring to the accompanying drawings for a more complete explanation of my invention, Figure 1 is a vertical longitudinal 25 section of my drier, the cars being in elevation. Fig. 2 is a detail of one car and the inlet-passage for the heated air and controlling-valves therefor. Fig. 3 is a detail perspective of valves H.

30 A is the chamber or box of the drier, having an entrance a at one end and an exit a' at the other end. It has also an escape-flue a². In this chamber are tracks B, upon which travel the receptacles or cars C, which carry 35 the fruit-trays. Under the chamber or box is a hot-air conduit D, which extends its whole length, and is preferably made with an upwardly-sloping bottom in order to facilitate the flow of the heated air to the extreme end.

40 This conduit receives its heated air at the end d from any suitable furnace or source of heat, unnecessary herein to show. In the top of this conduit and at intervals throughout its length are the outlet-openings e, which are 45 controlled by the two-part valves E. These valves are hinged on opposite sides of the outlet-openings and fall to the center to close them, in this position resting on a fixed ledge e'. The outlet-openings extend across the 50 full width of the cars above, and their valves

are operated by the series of sliding bars F, which extend to the end of the drier and may be operated in any suitable manner. These bars are independent, there being one for each valve. The connection between the sliding 55 bars and valves is by means of an arm f, secured to one part of the valve, and the link f', secured to the other part of the valve. The link has a stud f² playing in a slot f³ in the arm, and the lower end of the arm is engaged 60 on each side by pins f⁴ in the sliding bar. By moving the bar in one direction the valve is opened, and by moving it in the other direction the valve is closed, and thus the valve of each outlet from the underlying air-passage 65 may be operated separately.

The cars C have on each side at their bases downwardly-extending flange-plates G, between which the valve E plays, said plates thus forming end wells of the outlet-passages. 70 Under the bottom of the cars are the transverse cleats g, against which the valves rest when in a vertical position, said cleats and valves thus forming the side walls of said outlet-passages. The cars are each made with 75 upwardly-tapering front and back walls, and the trays c are arranged therein, as shown, to form an upwardly-tapering air-space c' across the car, the lower end of said space communicating with the outer passages from the hot-air passage below. The trays are in vertical series, and on account of the tapering shape of the car the inner ends of the trays overlap or intersect different vertical planes. The spaces between the trays communicate at 80 their inner ends with the central air-space c' of the car and at their outer ends these spaces are controlled by the valves H. These valves, which are made of parallel strips, each consists of two members, one fixed and the other 85 movable, the latter being connected with the fixed member by pivoted links h, and its movement being similar to the movement of parallel rulers. The members fit together by corresponding rabbets h'. When the swinging member is moved close up to the fixed member, it opens a space between itself and the fixed member of the valve below, and when moved down it closes said space, though 90 without opening any space between itself and 95 the fixed member of the valve above. The 100

its own fixed member, as the rabbets h' are long enough to avoid this. The bottoms and tops of the cars are tight. The sides are also tight and consist of removable plates c^2 , held in place by buttons c^3 , and provided with swinging doors c^4 , whereby the fruit may be inspected from time to time. The removable side plates provide for the insertion of the fruit-trays, and one or both sides may be made removable.

The operation of the drier is as follows: The cars being laden are run into the box or chamber A, which may or may not be airtight. They pass in at one end and emerge from the other end. Their movement is periodical—that is, as a fresh car is entered all the cars within are moved up one place, so as to stand over an outlet-passage from the hot-air conduit below. In making this movement the valves E are all closed, so as not to interfere with the cleats on the car-bottoms. Then when the cars are in place the valves or any number, or any one of them may be opened, as circumstances require. This gives the operator complete control. If he finds that the fruit of any one or more cars is well dried before they have reached the exit, he can keep the valves over which said cars may be standing closed, and he may open any valve to continue the supply of heated air to any car he chooses. The swinging valves, the flange-plates, and the cleats form complete passages to supply the cars from the underlying hot-air conduit.

The hot air is directed upwardly into the cars, passing into their central space, and from thence it is equally distributed in the spaces between the overlapping trays, passing forwardly and backwardly through said space and out through the end valves H of said cars, being controlled in any space by said valves. The hot air thence passes out through the escape-flue a^2 of the chamber or box A.

Having thus described my invention, what I claim as new, and desire to secure by Letters Patent, is—

1. In a drier, and in combination with a receptacle for the material, an underlying hot-air conduit having an opening communicating with said receptacle, and the means for controlling said opening, consisting of the swinging two-part valve E, the sliding bar F, the arm connected with one part of said valve

and operated by the sliding bar, and a link connected with the other part of said valve, 55 and a sliding connection connected with the arm of the other part, substantially as described.

2. In a drier, and in combination with a series of movable receptacles or cars for the material, an underlying hot-air conduit having openings at intervals communicating with the receptacles or cars above, the two-part swinging valves E, controlling said openings, the independent sliding bars F, for separately 60 operating said valves, the slotted arms connected with one part of the valves and operated by the sliding bars, and the links connected with the other part of the valves and having pins working in the slotted portions 70 of the arms, substantially as described.

3. In a drier, the receptacle or car for the material, and the underlying hot-air conduit having an opening communicating with said receptacle or car, in combination with the 75 swinging two-part valve E, controlling the opening, and the side flange-plates, and the cross-cleats on the receptacle or car forming with said valve a communicating-passage from the hot-air conduit to the receptacle or car, 80 substantially as described.

4. In a drier, a car for the material, having a closed top and sides, a central air-space receiving heated air at its base, and a series of separated trays in front and back of said space, in combination with valve-controlled 85 openings in its front and back, whereby the passage of air between the trays may be controlled, substantially as described.

5. In a drier, the car for the material, having a closed top and sides, a central air-space receiving heated air at its base, and a series of separated trays in front and back of said space, in combination with openings in the front and back walls of said car, and the 95 valves controlling said openings, consisting of a fixed rabbeted strip and a movable rabbeted strip connected with the fixed strip by pivoted links, substantially as described.

In witness whereof I have hereunto set my hand.

ELTON R. SHAW.
